UNITED STATES PATENT OFFICE.

JOHN ERICKSON, OF WHITE EARTH, NORTH DAKOTA.

PRESS-BIT BRIDLE.

1,133,115.

Specification of Letters Patent. Patented Mar. 23, 1915.

Application filed September 16, 1913. Serial No. 790,028.

To all whom it may concern:

Be it known that I, JOHN ERICKSON, a subject of the King of Sweden, residing at White Earth, in the county of Montraille and State of North Dakota, have invented 5 certain new and useful Improvements in Press-Bit Bridles; and I do hereby declare the following to be a full, clear, and exact description of the invention, such as will 10 enable others skilled in the art to which it appertains to make and use the same.

My invention relates to new and useful improvements in bridles and bits and consists of a bridle and bit of the type that are 15 adapted to exert a pressure upon the side of the horse's nose, thus doing away with the usual mouth bit.

An important object of my invention is to provide a bit and bridle of the character described 20 that will eliminate the use of the ordinary mouth bit and be as efficient and reliable in its operation, so that the driver in pulling the reins will cause the bit of my improved construction to press against the 25 side of the horse's nose, and thus guide the horse as desired.

A further object of my invention is to eliminate the use of a mouth bit, which is 30 extremely objectionable in cold weather, as the tongue of the animal often adheres to the bit.

An object of equal importance is to provide a bridle such as described, which is 35 constructed of few parts reliable and efficient in its operation and cheap to manufacture.

The above and additional objects are accomplished by such means as are illustrated in the accompanying drawings described in 40 the following specification and then more particularly pointed out in the claims which are appended thereto and form part of this application.

With reference to the drawings, wherein, 45 I have illustrated the preferred embodiment of my invention as it is reduced to practice, and throughout the several views of which, similar reference numerals designate corresponding parts: Figure 1 is a side elevation 50 of my entire device as it would appear in assembled operative position showing the member 24 thrown out of operative position for the sake of clearness. Fig. 2 is a front elevation of my device, Fig. 3 is a side elevation illustrating in detail one of the pressers 55 and operating mechanism therefor in a posi-

tion when pressed against the nose of a horse and showing the position of the presser when in spaced relation to the nose illustrated in dotted lines, Fig. 4 is a longitudinal sectional view taken on line 4—4 of Fig. 1.

Referring to the drawings by numerals, 1 designates the nose band forming a part of the bridle. This nose band 1 is adjustable by means of a plurality of studs, designated 2 as an entirety, that are carried in spaced relationship upon one of the terminals of the band and are adapted to be inserted through certain of a plurality of rectangular openings designated 3 as an entirety, that 70 are formed in the other terminal of the nose band in spaced relation. A rectangular plate 4 is secured in any suitable manner to the terminal of the band 1 carrying the openings 3 and is provided with openings 75 similar to the openings 3, which register therewith. This plate 4 forms a bearing for the studs 2, that are pivotally secured to the band 1 so that they may be operated for locking and unlocking position.

The bridle connected with the nose band 1 consists of the usual throat latch 5, cheek straps 6, nose strap 7, and brow band 8. The nose straps 7 are secured in any suitable manner to the rear edge of the band 1, 85 while the throat latch and brow band are secured to the cheek straps in any desirable manner. A pair of blinders designated 9, as an entirety, connected by a suitably stiff leather covered wire 10, are detachably secured to each of the cheek straps 6, by means of the hooks and eyelets 9' and 10' that are secured to the blinders 9 and the cheek straps 6.

A pair of presser members designated 11 95 and 12 respectively are secured upon opposite sides of the nose band 1 and are held outwardly from the band 1 by the mechanism for operating them, that is secured to opposite sides of the band 1. These presser members and mechanism for operating them are identical in construction and arrangement and it is thought necessary to describe only one of them. The presser member 12 is provided terminally with enlarged circular portions 13 and 14, that are adapted to engage the side of the horse's nose. A rod, designated 15, is mounted for rotation upon bearing members 16 and 17, that are secured to the side of the band 1. These bearing 100 members 16 and 17 consist of a pair of plates that are spaced by the rod 15 and secured in

aligned arrangement to the sides of the band 1, in spaced relation thereupon adjacent each side edge thereof. A loop, or eye, 18 is formed integral with the rod 15, adjacent the bearing member 16 as will be clearly seen with reference to Fig. 3, and forms means for holding the rod 15 in the position above described and preventing its withdrawal from the bearing member. This rod 15 extends outwardly from the band 1 and is secured at its free terminal as at 19 to a pin 20, that is inserted transversely through the center of the member 12, in which a recess 21 is formed to provide for the securing of the free terminal of the bar 15 to the pin 20. A loop or eye 22 is formed integral with the bar 15 adjacent its rear terminal and affords means for securing a ring or eyelet 23, that is adapted to be secured to the driving rein. This eye 23 consists of a single piece of wire bent intermediate its ends to form a loop or eye 24 and turned about the member 22 at its free terminal as at 25. A rod 26 is journaled in the bearing member 16 in the enlarged portion 27 thereof and is secured at its free terminal to an eye 28, mounted upon the lower portion of the member 12 adjacent the portion 14 thereof. The enlarged portion 27 of the bearing member 16 is provided centrally with an opening through which extends a loop 29, formed integrally with the rod 26. A connecting rod 30 is secured terminally to the loops 18 and 29 of the bars 15 and 26 respectively. It will thus be seen that any movement of the bar 15 will likewise move the bar 26. The portions of the rod 15 and 26 extending outwardly from the member 1 are designated 31 and 32 respectively, and so curved as to cause the pressing member 12 to bear evenly against the nostrils of the animal, when the rods 15 and 26 are rotated.

It is desirable to provide some means for restraining the horse from lowering its head, when the bridle is attached thereto, and in this connection there has been provided, a rod 33, that is journaled for sliding movement in the bearing members 17 at the lower terminal thereof. This rod 33 extends outwardly from the band 1 and is provided at its outer terminal with an eyelet 34 that is adapted to have secured thereto the check rein 35. The forward terminal of this rod 33 is provided with an eye 36, which serves to prevent the withdrawal of the rod 33 from the bearing 17. A rod 37 is pivoted so as to be normally disposed at right angles to the rod 33, by bending the rod intermediate its end about a screw 38 that is turned into an enlarged portion 39 formed on the bearing member 17. The rod 37 is connected at its lower terminal to the eyelet 36. The upper portion of this rod 37 is bent essentially at right angles to the lower portion thereof as at 40. The portion 40 of the rod 37 is disposed above and in engagement with the loop 22 formed adjacent the rear terminal of the rod 15. The rod 32 is to be moved laterally with respect to the band 1 and this movement is brought about when the horse lowers its head. It will thus be seen that when the horse lowers its head, the slack on the check rein 35 is taken up, thus moving the rod 33 whereby the rod 37 acting as a lever and the portion 40 engaging the loop 22 of the bar 15, will cause the bar 15 to be rotated and consequently subject pressure upon the horse's nose by forcing the member 11 into pressing engagement therewith.

The driving reins, not shown, are to be attached to the members 24 and when pulled will cause the rods 15 and 32 to press the presser members 11 and 12 in engagement with the nostrils of the horse.

In reduction to practice I have found that the form of my invention, illustrated in the drawings and referred to in the above description, as the preferred embodiment is the most efficient and practical; yet realizing that the conditions concurrent with the adoption of my device will necessarily vary, I desire to emphasize the fact that various minor changes in details of construction, proportion and arrangements of parts may be resorted to, when required, without sacrificing any of the advantages of my invention, as defined in the appended claims.

Having thus described my invention, I claim:

1. In a bridle of the character described the combination with a nose band of a pair of presser members pivoted thereto, a pair of rods journaled upon opposite sides of said nose band connected with said pressers centrally of the ends thereof, eyelets connected with said rods and adapted to be secured to the reins, a second pair of rods operatively connected with said first named rods and the lower terminals of said pressers, and means for causing said pressers to bear against the nose of the horse, operated when the horse lowers its head.
2. In a bridle of the character described the combination with a nose band of a pair of presser members secured thereto, a plurality of curved rods carried upon each side of said nose band and connected with the presser members, said rods connected centrally and at the lower terminals of said presser members in spaced relation to each other, one of said rods adapted to be connected with the driving reins, and means for causing the presser members connected with said rods to press against the nostrils of the horse.
3. In a bridle of the character described the combination with a nose band of a pair of presser members secured thereto, said presser members provided terminally with enlarged portions, means for causing said

presser members to be pressed against the sides of the nostrils of the horse, mounted upon said nose band connected with said presser members, and spacing them from 5 said nose band, and means connected with the check rein of a bridle for causing the presser member to be pressed in engagement with the nostrils of the horse, should the animal lower its head.

10 4. A bridle including a nose band, presser members secured to the nose band, means for causing said presser members to be pressed against the sides of the nostrils of the horse consisting of rods rotatably journaled on 15 the nose band and pivotally connected with

the presser members at points adjacent certain ends of the presser members and the central portions thereof, a right angularly extending loop formed on each of the rods, a link connecting the loops with each other, 20 and means to rotate both of the rods to cause the presser members to engage the sides of the horse's head.

In testimony whereof I affix my signature in presence of two witnesses.

JOHN ERICKSON.
